UNITED STATES PATENT OFFICE.

JEAN R. KRAUSE, OF NEW YORK, N. Y.

DESIGN FOR A HAIR-FRONT.

SPECIFICATION forming part of Design No. 12,617, dated December 20, 1881.

Application filed November 14, 1881. Term of patent 7 years.

To all whom it may concern:

Be it known that I, JEAN R. KRAUSE, of the city, county, and State of New York, have invented a new and original Design for a Hair-
5 Front, of which the following is a full, clear, and exact description, reference being had to the accompanying drawing, making part of this specification.

The nature of my invention is clearly shown
10 in the accompanying drawing, to which reference is made.

This invention relates to an improved design of hair-front for ladies' wear; and it consists of a parted hair-front having symmetrically-
15 arranged curls and wave-scallops arranged below the same.

A A in the drawing represent the symmetrically-parted sections of my improved hair-front, which are provided at both sides of the

parting with one or more so-called "spit-curls," 20 B, and below the same with wave-scallops C. The sections A A extend from the parting down to the ear, and are finished by the curls and wave-scallops in a very ornamental manner.

Having thus described my invention, I claim 25 as new and desire to secure by Letters Patent—

The design for a hair-front, consisting of centrally-parted sections A A, having one or more symmetrically-arranged curls, B, and wave-scallops C below the curls, substantially as shown 30 and described.

In testimony that I claim the foregoing as my invention I have signed it this 3d day of November, 1881.

JEAN R. KRAUSE.
